UNITED STATES PATENT OFFICE.

MATTHEW SERDYN, OF ROYAL OAK, MICHIGAN.

DAMPER FOR FIREPLACES.

Application filed July 19, 1927. Serial No. 206,911.

This invention relates to dampers for fire places and has for an important object thereof the provision of a damper casing for fire places, providing an efficient guide for use by masons in the construction of the fire place.

A further object of the invention is to provide a device of this character so constructed that the necessity for plastering or otherwise heat-insulating the rear wall of the damper is eliminated and a construction provided which may be readily cleansed.

A further object of the invention is to provide a damper construction, wherein the damper shelf provides not only a mounting for the usual damper, but likewise provides a receptacle for the collection of soot.

A further object of the invention is to provide in combination with the damper shelf a movable damper element which may be employed to remove from the damper shelf any collected soot.

These and other objects I attain by the construction shown in the accompanying drawings, wherein for the purpose of illustration is shown a preferred embodiment of my invention and wherein:

Figure 1 is a front elevation of a fire place embodying a damper constructed in accordance with my invention;

Figure 2 is an enlarged sectional view on the line 2—2 of Figure 1;

Figure 3 is a vertical sectional view through the damper element on the line 3—3 of Figure 2;

Figure 4 is a perspective view of the damper plate.

Referring now more particularly to the drawings, the damper casing is formed of sheet metal, the sides 10 of which converge upwardly, so that they are spaced apart at their lower ends a distance equal to the width of the fire place with which they are to be employed and at their upper ends a distance equal to the width of the chimney which is to be employed. At their lower ends, these side walls have out-turned flanges 11 adapted to enter between courses of the masonry 12 from which the fire place is formed and at their upper ends have upwardly extending flanges 13 adapted to enter between and closely engage against opposed sides of the flue lining 14 of the chimney.

The front wall of the casing has an intermediate vertical section 15 forming the front wall of the front of the damper casing. Be-

low this intermediate section, the front wall inclines outwardly and downwardly, as indicated at 16, and has, at the lower end of this outwardly and downwardly inclining section, a horizontal outwardly extending flange 17 forming the support for the masonry above the fire place. Above the throat forming section, the front wall inclines upwardly and rearwardly, as indicated at 17^a and the upper end of this upwardly and rearwardly extending section has a vertically extending flange 18 extending into and fitting against the flue lining at the front wall thereof. It will be noted that the inclined portion 17 and the inclined side members will form a support upon which the lower end of the flue lining may be seated.

The rear wall of the damper casing has an intermediate vertically extending throat forming section 19 which is considerably shorter than the vertical section 15 of the front wall and has its lower end spaced slightly above the lower end of the vertical section of the front wall. Below the section 19, the rear wall inclines rearwardly and downwardly, as indicated at 20, and this rearwardly and downwardly inclining section has at its lower end a horizontal rearwardly directed flange 21 adapted to enter between courses of the masonry of the rear wall 22 of the fire place. At the upper end of the vertically extending section 19, the rear wall extends horizontally rearwardly, as indicated at 23, to form the damper shelf, the forward edge of which projects slightly forwardly of the vertical line of the forward wall of the flue lining and the rear edge of which connects to a second vertically extending section 24, the upper end of which extends into the flue lining and fits against the rear wall thereof. It will be obvious that with a damper casing of this construction, the mason can exactly follow the outline of the outer face of the damper casing in the construction of the fire place and thereby form an accurate and properly operating throat and shelf for the fire place.

In combination with a damper casing of this structure, I provide a damper plate 25 of the same size as the horizontally extending portion 23 of the rear wall and adapted to seat thereon. This plate has secured thereto adjacent its side edges handles 26 which are shaped to conform to the shaping of the rear wall and lie closely thereagainst. By means of these handles, the damper plate

may be moved to close the throat 27 of the damper or may be moved forwardly and then tilted, as indicated in Figure 2, to cause soot which has collected upon the upper surface thereof to discharge downwardly through the throat to cleanse the shelf. To assist in the cleansing operation, the interior of the front wall adjacent the bottom of the vertical section 15 thereof is provided with hooks 28, by means of which a receptacle for the reception of this soot may be supported.

In order to permit tilting of the plate 25, the rear corners of the side edges are cut away, as indicated at 29, providing the clearance necessary, due to the convergence of the side walls 10. Attention is directed to the fact that with the construction above recited, upwardly moving currents of heated air engaging against the rear wall 30 of the fire place will move upwardly in close contact to the rear wall of the damper and will not tend to engage against the front wall below the vertical wall 15, so that there is no tendency to baffling circulation of the smoke in the lower end of the damper casing. The course of the smoke, in passing from the fire place, is indicated by arrows in Figure 2, and it will be noted that since the smoke and heated air have a tendency to cling to the front wall during its upward passage, a pocket is provided at the rear of the chimney, permitting a down draft, as indicated by the arrows, by means of which soot removed from the products of combustion may be carried to the shelf 25 and deposited thereon. This current of air will serve to prevent overheating of the rear wall 24, thus eliminating the necessity for plastering or otherwise fire-proofing this rear wall.

Since the construction hereinbefore set forth is capable of a certain range of change and modification without materially departing from the spirit of the invention, I do not limit myself to such specific structure except as hereinafter claimed.

I claim:

1. A sheet metal damper casing comprising side, front and rear walls, the side walls converging upwardly, the front and rear walls embodying confronting vertical portions combining with the side walls to produce a throat, the vertical section of the rear wall being of considerably less length than the vertical section of the front wall and having its lower end disposed slightly above the lower end of the vertical section of the front wall, the rear wall from the upper end of the vertical section extending horizontally rearwardly to provide a damper shelf.

2. A sheet metal damper casing comprising side, front and rear walls, the side walls converging upwardly, the front and rear walls embodying confronting vertical por-

tions combining with the side walls to produce a throat, the vertical section of the rear wall being of considerably less length than the vertical section of the front wall and having its lower end disposed slightly above the lower end of the vertical section of the front wall, the rear wall from the upper end of the vertical section extending horizontally rearwardly to provide a damper shelf, the front wall at the upper end of its vertical section having an upwardly and rearwardly inclining section the inner upper edge of which slightly overlaps the damper shelf.

3. A sheet metal damper casing comprising side, front and rear walls, the side walls converging upwardly, the front and rear walls embodying confronting vertical portions combining with the side walls to produce a throat, the vertical section of the rear wall being of considerably less length than the vertical section of the front wall and having its lower end disposed slightly above the lower end of the vertical section of the front wall, the rear wall from the upper end of the vertical section extending horizontally rearwardly to provide a damper shelf, a damper plate seated upon the damper shelf and control elements for the damper plate and extending downwardly through the throat of the damper casing.

4. A sheet metal damper casing comprising side, front and rear walls, the side walls converging upwardly, the front and rear walls embodying confronting vertical portions combining with the side walls to produce a throat, the vertical section of the rear wall being of considerably less length than the vertical section of the front wall and having its lower end disposed slightly above the lower end of the vertical section of the front wall, the rear wall from the upper end of the vertical section extending horizontally rearwardly to provide a damper shelf, the lower ends of said vertical portions being disposed above the lower end of the damper casing, the throat and rear walls below their vertical portions diverging downwardly.

5. A sheet metal damper casing comprising side, front and rear walls, the side walls converging upwardly, the front and rear walls embodying confronting vertical portions combining with the side walls to produce a throat, the vertical section of the rear wall being of considerably less length than the vertical section of the front wall and having its lower end disposed slightly above the lower end of the vertical section of the front wall, the rear wall from the upper end of the vertical section extending horizontally rearwardly to provide a damper shelf, the lower ends of said vertical portions being disposed above the lower end of the damper casing, the throat and rear walls below their vertical portions diverging

downwardly, a damper plate seated upon the damper shelf and control elements for said plate extending downwardly through the throat of the damper casing and conforming in shape to the rear wall of the damper.

6. A sheet metal damper casing comprising side, front and rear walls, the side walls converging upwardly, the front and rear walls embodying confronting vertical portions combining with the side walls to produce a throat, the vertical section of the rear wall being of considerably less length than the vertical section of the front wall and having its lower end disposed slightly above the lower end of the vertical section of the front wall, the rear wall from the upper end of the vertical section extending horizontally rearwardly to provide a damp-

er shelf, the lower ends of said vertical portions being disposed above the lower end 20 of the damper, the throat and rear walls below their vertical portions diverging downwardly, a damper plate seated upon the damper shelf and control elements for said plate extending downwardly through the 25 throat of the damper casing and conforming in shape to the rear wall of the damper casing, the corners of the rear ends of the side edges of the plate being cut-away to thereby permit oscillation of the plate to discharge soot supported thereby through the 30 throat of the damper casing.

In testimony whereof I hereunto affix my signature.

MATTHEW SERDYN.
